CORSELETTE OR THE LIKE

Irving Gimble and Daniel Musano, Corona, N. Y.

Application December 4, 1957, Serial No. 48,775

Term of patent 7 years

(Cl. D20—2)

We claim:

The ornamental design for a corselette or the like, substantially as shown.
